UNITED STATES PATENT OFFICE.

FREDERICK A. ZIMMER, OF COVINGTON, KENTUCKY.

POULTRY-FEEDER.

1,099,331.

Specification of Letters Patent. Patented June 9, 1914.

Application filed December 22, 1910. Serial No. 598,682.

To all whom it may concern:

Be it known that I, FREDERICK A. ZIMMER, a citizen of the United States, residing at Covington, in the county of Kenton and 5 State of Kentucky, have invented certain new and useful Improvements in Poultry-Feeders, of which the following is a specification.

My invention relates to feed troughs, and 10 its object is to improve the construction of feeders for supplying feed to poultry, such as chickens and pigeons, in such a manner as to protect it from contamination, especially by the scratching and scattering by the 15 birds.

My invention consists in the details of construction and arrangement hereinafter more fully described and claimed.

In the drawings: Figure 1 is a perspective view of sheet metal feeder embodying my improvements, parts of the end and the barrier being represented as broken away to reveal the interior construction. Fig. 2 20 is a vertical cross section through the feeder shown in Fig. 1, the dotted lines indicating the relation of the feeder to the birds. Fig. 25 3 is a detail perspective view illustrating how the bottom, with its lateral barriers and its longitudinal corrugations, is attached to the end, according to my invention.

As illustrated in the drawing, the feeder comprises the longitudinally corrugated bottom 1, attached to upright ends 2, between which are supported the downwardly 30 converging sides 3, forming a hopper. The bottom has three of the corrugations, the middle one, 1^a, being higher than the other two corrugations, 1^b, one of which is on each side of the middle corrugation 1^a. All three 35 corrugations are of substantially triangular cross section, their sides slanting down at an angle of about 45 degrees with the bottom 1, itself, and they extend from end to end of said bottom. A space is left between 40 the large, middle corrugation and the adjacent smaller corrugation on each side, forming a gutter, 1^c; the bottom of this gutter is, preferably, substantially flat, and it also extends uninterruptedly from end to end of 45 the bottom 1, between the laterally disposed corrugations or ridges 1^b, and the middle ridge 1^a. Past the ridges 1^b, the bottom 1 extends horizontally for a distance somewhat more than the width of the gutter 1^c, 50 to the lateral barriers 1^d, so that troughs 1^e are formed, having substantially flat bot-

toms. The barriers 1^d extend substantially vertically to a height somewhat in excess of that of the middle corrugation or ridge 1^a, and also extend to the full length of the 60 bottom 1.

The ends 2 abut against the ends of the bottom 1 and of its corrugations or ridges 1^a and 1^b, and have horizontal in-turned flanges 2^a along their lower edges, taking 65 under the end parts of the bottom 1, and secured thereto by suitable bolts or rivets 2^{a'}. These flanges stiffen the bottom 1, transversely. These ends 2, also have flanges 2^b, along their vertical sides, and 70 these come inside the lateral barriers 1^d, and are secured thereto by suitable bolts or rivets, 2^{b'}. These support and reinforce the barriers 1^d, and complete the attachment of the ends 2 to the bottom 1. The manner in 75 which the flange 2^a of the end 2 comes under the bottom 1, and the flange 2^b of said end, comes outside the barrier 1^d of said bottom, is shown in Fig. 3. It will be seen that this arrangement produces a very strongly 80 reinforced corner at this point, where it is most needed.

The sides 3 of the feeder are attached to the ends 2 by their inturned flanges 3' and, converging downwardly, have their upper 85 edges 3^a alined with the upper corners 2^c of the ends 2, but their angle of convergence is such that, if continued down to the bottom 1, they would meet it, respectively at the inner sides of the gutters 1^c, where these 90 gutters terminate in the upwardly slanting sides of the middle larger corrugation or ridge 1^a. However, these sides do not extend to the bottom, but terminate short thereof, so that longitudinal spaces 3^b are 95 left of height about equal to that of the middle ridge 1^a. This constitutes the throat for the egress of the feed from the hopper, as it is eaten by the birds. To lessen the opening of this throat, slides 4, extending 100 from one end 2 to the other, and lying flat against the outside of the sides 3, are mounted in guides 4^a, secured to the ends 2, so as to slide up and down and open or close the spaces or throats 3^b. These slides, if brought 105 down to engage with the bottom 1^a, will meet it at the inner side of the gutter 1^c, as aforementioned. To hold the slides 4 in adjusted positions, the slots 4^b, are provided in the slides, and bolts with thumbnuts 4^c, 110 are mounted in the sides 3, near the middle of the feeder. The slides have out-turned

flanges 4^a, on their upper edges, to stiffen them horizontally, and to serve as handles.

Partitions 5, may be provided in the hopper, their number depending on the length 5 of the feeder. They are attached to the sides 3, by three flanges, 5^a, on their upright edges, and they extend down and have their lower parts, 5^b, notched to conform to the middle ridges, 1^a, which they embrace, or 10 straddle. These partitions, 5, brace the sides 3, and by their engaging with the ridge 1^a, they brace and strengthen the entire feeder without the necessity of otherwise securing them to the bottom 1.

15 The roof or lid 6, of the feeder, extends well out over the sides and ends of the hopper, and has the transverse battens 6^a which conform to the lower side of the roof, and are positioned just outside the upper parts 20 of the ends 2. The roof 6 is hinged to the hopper by suitable pivots 6^b, passing through the battens 6^a, and the ends 2, at one side of the feeder, so that the roof may be laid back, and will remain open for putting feed into 25 the hopper, as shown in Fig. 1. The dotted lines in Fig. 1 indicate the roof or lids 6, in lowered or closed position. This form of covering for the feeder is especially adapted to exclude moisture and contamination 30 as well as vermin. The only other access to the feed is through the spaces or throats 3^a, as adjusted by means of the sides 4.

The principle of operation of the middle parting ridge, in conjunction with the adjustable lateral throat, is well-known in the 35 art, especially in the feeding of horses, cattle, hogs, and similar live stock. These elements, combined with the others above described, make up a feeder especially suitable 40 for feeding poultry and other birds. By

such means, the birds are prevented from contaminating and wasting the feed, while at the same time, screens or other obstructions in the throat are dispensed with, and their injurious effects avoided.

45 An especially desirable result of my improved feeder construction, as herein set forth, is the attainment of extreme lightness, with ample strength and rigidity. Moreover, the feeder may be assembled with little 50 difficulty, as is desirable in such an article. Many of these feeders must be transported long distances, unassembled, to save in cost of transportation, and many localities where they must be used are remote from the 55 means of assembling more complicated constructions.

Having fully described my invention, I claim:

60 In a poultry feeder, a bottom composed of a single rectangular sheet, formed, from end to end, with longitudinal parallel corrugations, with flat regions flanking the corrugations, and with upright barriers terminating said bottom laterally, adjacent the 65 flat regions, upright sides forming a hopper and having their lower edges spaced from said bottom, and upright ends for the feeder, each of said ends closely abutting respective 70 ends of the bottom and sides and having a lower flange underlapping said end of the bottom from side to side and secured to the flat regions thereof, and having upright flanges embraced within the barriers of the bottom and secured thereto.

FREDERICK A. ZIMMER.
